UNITED STATES PATENT OFFICE.

CHARLES L. RODGERS, OF NEWTON, KANSAS.

FUEL-HEATING DEVICE FOR INTERNAL-COMBUSTION ENGINES.

1,240,372.

Specification of Letters Patent. Patented Sept. 18, 1917.

Application filed October 2, 1916. Serial No. 123,386.

To all whom it may concern:

Be it known that I, CHARLES L. RODGERS, a citizen of the United States, residing at Newton, in the county of Harvey and State 5 of Kansas, have invented certain new and useful Improvements in Fuel-Heating Devices for Internal-Combustion Engines; and I do declare the following to be a full, clear, and exact description of the invention, such 10 as will enable others skilled in the art to which it appertains to make and use the same.

This invention relates to a fuel heating device for internal combustion engines, by the 15 use of which, kerosene and heavier hydro-carbon oils or liquids may be used as a fuel for the same. As a feature of the invention, the exhaust from the explosive engine is utilized as a means for the heating of heavy 20 oil, and converting the same into a gas or vapor before it is introduced into the firing cylinders.

Another object of the invention is to provide a device of this character which may be 25 readily applied to or removed from explosive engines of any construction or character, and one which may be readily and easily taken apart for cleaning or repairs.

An additional object of the invention is 30 to provide an attachment for internal combustion engines which will act to thoroughly mix the mixture in addition to thoroughly heating the same.

A further object of the invention is to generally improve upon devices of this character by providing a device which will be extremely simple, durable, and inexpensive in construction, and one which will be efficient and reliable in operation, and well adapted 35 to the purpose for which it is designed.

With these and numerous other objects in view, the invention consists of certain novel features of construction and the combination and arrangement of parts as will be herein- 40 after fully described and claimed.

The accompanying drawings illustrate the construction of the preferred form of the invention and the manner in which the same is applied to an internal combustion engine, 45 and wherein:

Figure 1 is a front elevation of a conventional internal combustion engine, showing a device constructed in accordance with this invention applied thereto;

Fig. 2 is a side elevation of the same;

Fig. 3 is a vertical sectional view of the device detached from the engine; and

Fig. 4 is a horizontal sectional view of the device taken on the plane indicated by the line 4—4 of Fig. 3.

Referring more particularly to the drawings in which like parts are designated by similar reference characters throughout the several views, the numeral 1 represents a hollow casing which is preferably made 65 square-shaped in configuration and of steel, brass, or any other suitable material. The ends of the casing 1 are provided with a plurality of apertures 2 in which are snugly fitted and secured in any suitable manner the 70 ends of a plurality of tubes or pipes 3. As shown, the tubes 3 extend longitudinally through the casing 1 and are staggeredly arranged when viewed from the side to provide an efficient fuel mixing device to be 75 more fully hereinafter explained. Two of the opposite sides 4 of the casing are provided with openings 5, the opening 5 in one of the sides being adapted to receive the short pipe section or nipple 6 leading from 80 the carburetor of the internal combustion engine, while the opening 5 in the other side of the casing is adapted to receive a similar pipe section 7 leading to the intake manifold of said engine.

Arranged at the ends of the casing 1 are cap members 8 and 9 composed of end plates 10 and flanges 11, the latter having their free edges abutting the ends of the casing 1 as clearly shown by the drawings. The 90 ends 10 of the cap members 8 and 9 are provided with inlet and outlet openings 12 and 13 respectively, the opening 12 being adapted to receive one end of the exhaust pipe 14 leading from the engine, while the other 95 opening 13 is adapted to receive one end of an exhaust escape pipe 15. Extending longitudinally through the casing 1 and the cap members 8 and 9, are clamping bolts 16 having nuts 17 on their threaded free ends, 100 whereby said cap members are removably held in their assembled positions, with respect to the casing.

It is here to be noted that the cap members conform to the shape of the casing, but if 105 desired, they, together with the casing, may be made of any suitable shape. The number and size of tubes and size of the casing is to be determined by the type and size of engine in connection with which the device is to be 110

used. Furthermore the exact relative arrangement of the tubes is to be determined by the shape of the casing and also by the number of tubes used.

5 It has been found that when a device constructed in the manner above described is used in connection with an internal combustion engine, the heat radiated from the tubes 3 by the hot exhaust gases passing 10 through the same will be sufficient to completely vaporize the kerosene or other heavy hydrocarbon oils used as a fuel for the engine. As the fuel passes transversely through the casing and around the tubes, which 15 are, as previously explained, arranged staggered, it will be thoroughly mixed.

Another advantage of the invention resides in the fact that the device may be readily and easily taken apart for cleaning 20 or repairing, and also it may be readily and easily applied to or removed from an engine of almost any type.

From the foregoing description, taken in connection with the accompanying drawings, the construction and use of the invention will be readily understood without a more extended explanation.

As numerous changes in form, proportion, and in the minor details of construction, 30 may be resorted to without departing from the spirit of this invention, I do not wish to

be limited to the construction herein shown and described other than that set forth in the appended claim.

I claim:

A device of the class described comprising a hollow rectangular shaped casing having a plurality of apertures in the ends thereof, and gaseous fuel inlet and outlet openings in two of its opposite sides, a plurality of tubes extending longitudinally through said casing and having their ends secured in said apertures, rectangular shaped cap members composed of rectangular shaped end plates and inwardly extending lateral flanges, said end plates being provided with inlet and outlet exhaust openings, said cap members being arranged at the ends of said casing with their flanges abutting the same, and clamping bolts extending longitudinally 40 through said casing and said cap members for removably maintaining the latter in their assembled positions with respect to said casing.

In testimony whereof I have hereunto set 50 my hand in the presence of two subscribing witnesses.

CHARLES L. RODGERS.
